UNITED STATES PATENT OFFICE.

THOMAS POLIVKA, OF CHICAGO, ILLINOIS, ASSIGNOR TO THE AMERICAN MOSAIC BRICK AND TILE COMPANY, OF SAME PLACE.

TILE AND METHOD OF MAKING SAME.

SPECIFICATION forming part of Letters Patent No. 534,664, dated February 26, 1895.

Application filed August 27, 1892. Serial No. 444,270. (No specimens.)

To all whom it may concern:

Be it known that I, THOMAS POLIVKA, a subject of the Emperor of Austria-Hungary, residing at Chicago, in the county of Cook 5 and State of Illinois, have invented certain new and useful Improvements in Ornamental Tiles and other Like Articles and the Method of Making the Same, of which the following is a full, clear, and exact specification.

My invention relates to that class of ornamental tiles and the method of producing the same, whose ornamental surfaces are composed of individual blocks, sections or figures, contrasting with one another, and forming a design or configuration. In the production of ornamental surfaces of tiles of this description, it is common in the art to employ skeleton frames composed of different strips or sheets, usually of metal, set on edge, 10 and bent to form the division lines between the various blocks or figures of the ornamental surface. This skeleton frame is placed upon the bottom of a mold box or other like device having a smooth, level surface, or other 15 surface corresponding to the surface of the tile or article to be produced, and the compartments or cells of the frame formed by the strips are then filled with clay, composition, or other material, usually in a dry, powdered or 20 comminuted state, and of the desired shades or colors for the production of the design or ornamental face of the tile to be produced. After each compartment has been filled to the requisite depth with material of the proper 25 shade or color, the mold box is agitated or shaken, for the purpose of causing the material in each cell or compartment to settle evenly therein. The frame is then withdrawn from the box, leaving the material formerly 30 contained in the various cells or compartments standing in the form of little blocks or sections, with vacant spaces or interstices between them, such spaces or interstices of course being in the form of the skeleton frame 35 by which they are produced. Heretofore, at this stage of the process, it was customary to fill in on top of the blocks or sections so formed, a quantity of fire clay or tile clay, or 40 some other suitable substance, sufficient to 45 constitute the backing, or body of the tile or

brick, after which the whole is subjected to great pressure and finally baked. This backing material, as will be understood, is coarse, and consequently the particles thereof do not sink freely and intimately into the vacant 55 spaces or interstices between the blocks or sections constituting the ornamental face of the tile, and therefore when the tile is subjected to pressure, the said spaces close up, the walls of the sections or blocks meet, in 60 other words, and the blocks or sections are consequently distorted and their outlines rendered more or less ragged or irregular and indistinct, and they grow more so as the surface wears away until the symmetry of the 65 pattern is finally destroyed.

My invention is designed to overcome these evils, and it has for its primary object to prevent the distortion of the individual blocks or sections when subjected to pressure.

A further object of my invention is to provide the spaces or interstices between the blocks or sections with a filling which shall be co-extensive in depth with such sections and will wear away evenly therewith.

With these ends in view, my invention consists in certain features of novelty hereinafter more fully described with reference to the accompanying drawings, and particularly pointed out in the claims.

In the said drawings, which illustrate my improvements, and also the prior method, Figure 1 is a plan view of a portion of the skeleton frame ordinarily employed, the material and mold box being omitted. Fig. 2 is 85 a corresponding portion of the same design, illustrating my improved tile when manufactured according to my invention. Fig. 3 is a transverse section of a portion of the completed tile, manufactured according to my invention. Fig. 4 is a transverse section of the mold box and skeleton frame showing some of the compartments or cells of the frame partially filled with the material or composition of which the ornamental face is composed. 90 Fig. 5 is a transverse sectional view of a portion of the mold box illustrating the tile when manufactured according to the prior method, just before it is subjected to pressure; and Fig. 6 is a similar view of the same after it 95 100

is compressed and completed, showing the effect of the pressure on the individual blocks or sections of the ornamental surface.

Like signs of reference indicate like parts 5 throughout the several views.

In carrying out my invention, I employ a mold box A, in which is placed the skeleton frame, B, made up of a number of strips standing on edge and being variously arranged, as shown in Fig. 1, forming cells or compartments, C, into which latter the pulverized or comminuted material which is to form the ornamental surface of the tile is placed, all in the ordinary manner, as before 15 explained.

After the cells or compartments C have been filled to the proper depth with the ornamental facing material, and such material caused to settle evenly in each compartment, as before 20 explained, the skeleton frame B is carefully withdrawn from the box, leaving the facing material standing in separate blocks or sections, D, with narrow spaces or interstices E, between them, as shown in Fig. 5, it being of course understood that the cells or compartments C are only filled to a depth of from 25 one-sixteenth ($\frac{1}{16}$) to one-quarter ($\frac{1}{4}$) of an inch. Now according to the prior method, after the skeleton frame has been withdrawn 30 the coarse backing material F which forms the back or body of the tile or brick, is poured in on top of the sections D as shown in Fig. 5, and the whole is then subjected to pressure. The particles of the backing material 35 F being very coarse, as usual, do not readily settle into the spaces or interstices E, and when subjected to pressure, there being nothing to support the walls of the blocks D, the blocks are distorted, and their walls are 40 broken down and crowded together, or caused to meet as shown in Fig. 6, the backing material along the interstices sinking slightly downward as shown at f.

With a tile thus constructed, it will be 45 readily understood that as the ornamental surface composed of the blocks or sections D, wears away, such blocks will lose their symmetry, by reason of the distortion resulting from the pressure, and when the wear has 50 proceeded far enough to cut through the portions f, such portions will of course appear in the face of the tile, and greatly add to its disfigurement. In order to avoid this, and to provide each block with a distinct and clear 55 cut outline, I fill the interstices E as soon as the frame is withdrawn, and before the backing material is put on, with a very finely pulverized substance, consisting of the same or equivalent material as the blocks themselves 60 are composed of, but which may be of a contrasting shade or color. This filling, G, is carefully dusted into the interstices until the latter are completely filled even with the backs of the blocks or sections D, thus supporting the walls of such sections, and virtually 65 converting the whole ornamental surface into one firm mass. After this is accom-

plished, the backing F may be poured in with impunity, and the whole subjected to any desired degree of pressure without danger of 70 distorting the blocks or sections D or causing the backing to irregularly sink into the ornamental facing.

When a tile thus constructed has been completed by the ordinary baking process, the 75 surface thereof will be in close simulation of the species known as "mosaic." The filling G between the sections will wear away equally with such sections, and as such filling is co-extensive in depth with the ornamental surface 80 itself, it follows that the design will retain its identity, and the outlines of the sections and figures will remain sharp and clear cut as long as any of the ornamental surface is left on the backing. 85

Having thus described my invention, what I claim as new therein, and desire to secure by Letters Patent, is—

1. The method of making ornamental tiles, &c., which consists of forming a number of 90 blocks or ornamental figures, with spaces or interstices between them, of the material from which the tile is constructed, then filling such entrances with a similar material, then placing a backing over the whole, and finally subjecting the mass to pressure and solidifying it, substantially as set forth. 95

2. The method of making ornamental tiles, &c., which consists in forming a number of 100 blocks or ornamental figures with spaces or interstices between them from the material of which the surface of the tile is to be constructed, filling such entrances with a suitable dust or powder, then placing a backing over the whole, and finally subjecting the 105 mass to pressure and solidifying it, substantially as set forth.

3. The method of making ornamental tiles, &c., which consists in forming a number of 110 blocks or ornamental figures with spaces or interstices between them from the comminuted or pulverized substance of which the surface of the tile is to be constructed, filling such interstices with powdered material of a contrasting color, then placing a backing over 115 the whole and subjecting the mass to pressure and solidifying it, substantially as set forth.

4. As a new and useful article of manufacture, a tile or brick having an ornamental 120 surface consisting of a number of blocks or sections having rectilinear sides or walls, a filling between such blocks or sections composed of the same or equivalent material as the blocks themselves forming with the blocks 125 a solid vitrified mass coextensive in depth with the said blocks, and a suitable backing extending over the whole to form one hardened mass, substantially as set forth.

THOMAS POLIVKA.
